Primary Examiner — Wan Laymon

(57) **CLAIM**

The ornamental design for a hot water bottle, as shown and described.

DESCRIPTION

FIG. 1 is a perspective view of a hot water bottle showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in the drawings depict portions of the hot water bottle in which the design is embodied that form no part of the claimed design.
